UNITED STATES PATENT OFFICE

JOSEPH SACHS, OF WEST HARTFORD, CONNECTICUT

AUTOMATIC CIRCUIT BREAKER

Application filed January 16, 1929, Serial No. 332,925. Renewed February 26, 1931.

The invention relates particularly to an automatic circuit breaker of the type disclosed in my copending applications for Automatic circuit breakers, Serial No. 271,819 filed April 21, 1928, Serial No. 283,060 filed June 5th, 1928, and Serial No. 332,924 filed on even date herewith.

One of the objects of the invention is to provide a circuit breaker of the type disclosed in the said applications having a rectilinearly movable handle for operating a pivotally movable actuator and contact member. In accordance with the invention various improved details are provided whereby the before stated general object is effectively attained.

As disclosed in the third said application the automatic circuit breaking action takes place entirely independently of the operating handle and the said handle is nevertheless automatically moved to its open-circuit position whenever the circuit breaker is automatically operated to break the circuit. Thus after an automatic breaking of the circuit it is only necessary to move the handle in the regular way from its open-circuit position to its closed-circuit position in order to re-establish the circuit. One of the objects of the present invention is to provide such a circuit breaker wherein the means for actuating the movable contact member is pivotally movable and wherein the handle is movable rectilinearly.

A further object of the invention is to provide certain improved details of construction and mounting for the electric contacts, particularly the stationary contacts.

Other objects of the invention will be apparent from the following specification and claims.

In the accompanying drawings I have shown one embodiment of the invention similar in some respects to the disclosure in the said copending application, but it will be understood that the drawings are intended for illustrative purposes only and are not to be construed as defining or limiting the scope of the invention, the claims forming a part of this specification being relied upon for that purpose.

Of the drawings:

Fig. 1 is a front view of a circuit breaker embodying the invention, the enclosing cover being shown in section.

Fig. 2 is a side view of the parts shown in Fig. 1, the base and enclosing cover being shown in section.

Fig. 3 is a vertical sectional view taken along the line 3—3 of Fig. 2.

Fig. 4 is a transverse sectional view taken along the line 4—4 of Fig. 2.

Fig. 5 is a fragmentary perspective view showing the stationary and movable contacts and associated parts.

Figs. 6 and 7 are detail perspective views of the carbon contacts.

Fig. 8 is an enlarged fragmentary transverse sectional view taken along the line 8—8 of Fig. 3.

Figs. 9 and 10 are side views similar to Fig. 2 but showing the parts in different relative positions, the base and casing being omitted.

Referring to the drawings, it will be observed that the main body of the circuit breaker unit comprises two spaced side plates 1^b, 1^b and metallic cross members 2^b and 3^b threaded at their ends and connected with the side plates by means of nuts 4^b, 4^b. The said body of the circuit breaker unit is connected with a base 5^b by means of screws 6^b, 6^b extending through the members 2^b and 3^b and engaging metal plates 7^b and 8^b carried by the base. The said plates 7^b and 8^b are provided respectively with wire terminals 50^b and 51^b.

I provide a contact member which is movably mounted with respect to the body, preferably being mounted for pivotal movement. As illustrated the contact member includes two side plates 9^b, 9^b which are pivotally mounted upon a transverse rod 10^b supported at its ends by means of the side plates 1^b, 1^b of the body, the ends of the rod being reduced in diameter and extending through holes in the plates. The side plates 9^b, 9^b are spaced from the side plates 1^b, 1^b by means of washers 11^b, 11^b and are spaced from each other by means of bushings 12^b, 12^b surrounding the rod 10^b. The contact member is biased to its open-circuit position by means

of springs 19^b, 19^b surrounding the bushings 12^b, 12^b.

Suitable electric contacts are provided, there preferably being two stationary contacts carried by the body of the circuit breaker and two movable contacts carried by the contact member and adapted to be engaged with and disengaged from the respective stationary contacts. The stationary and movable contacts differ considerably from those disclosed in my said copending application, the contacts being arranged with their main contact faces perpendicular to the pivotal axis of the contact member instead of parallel therewith as heretofore shown and described. The main stationary contact 13^b at the right hand side is formed as a part of a metallic strip 13' which extends along the outer surface of the corresponding plate 1^b. As shown in detail in Figs. 5, 8 and 9 the strip 13' is held in place by means of the nut 4^b at the right hand end of the cross member 2^b. The said strip 13' is preferably longitudinally slotted as shown and the upper ends of the several sections of the strip are bent inward to extend through an opening in the side plate so as to provide contact faces adjacent the inner face of the said side plate. The left hand main stationary contact comprises a similar strip 13' and is similarly held by means of the nut 4^b at the left hand end of the cross member 2^b. The said left hand contact strip 13' is held in place by means of a flanged bushing 69 of conducting material so that the said contact strip 13' is electrically connected with the cross member 2^b and thus with the terminal 50^b. The right hand contact strip 13' is held in place by means of a flanged bushing 70 of insulating material interposed between it and the nut 4^b. Thus the said contact strip 13' is insulated from the cross member 2^b. The said strip 13' is electrically connected with the cross member 3^b at the opposite end by means of a conducting strap 71 which extends along the side of the side plate. Preferably a washer 72 of conducting material is provided to space the conducting strap 71 outward away from the contact member. The strap 71 is provided with an opening at one end through which the bushing 70 extends and with an opening at the other end for receiving the extended threaded portion of the cross member 3^b. Thus the right hand contact 13^b is electrically connected with the upper cross member 3^b and with the wire terminal 51^b. The main movable contacts 16^b, 16^b are connected with a transverse insulating member 17^b by means of screws 18^b, 18^b. Engaging each contact 16^b and located between it and the insulating member 17^b is a conductor 73, as shown in Figs. 5, 9 and 10, which serves as a means for the attachment 15 of the corresponding end of a U-shaped bi-

metallic strip 21^b. Screws 74, 74 are provided for holding the strip in place. Each of the said contacts 16^b extends outward through a hole in the corresponding side plate 9^b to provide an outer contact surface as shown, the end of the contact strip being carried backward through the hole and then along the inner surface of the side plate where it is held by means of a rivet 75. The contact faces of the contacts 16^b, 16^b are adapted to engage respectively with the contact faces of the contacts 13^b, 13^b as shown in Fig. 3.

An actuator 20^b is mounted upon the transverse rod 10^b between the two bushings 12^b, 12^b thereon. The bi-metallic strip 21^b normally engages the actuator 20^b and serves in and of itself as a normally operative mechanical connection between the actuator and the contact member. When the thermal strip is normally operative as a mechanical connection the actuator may control the movements of the contact member to its closed-circuit or its open-circuit positions for ordinary switching purposes. However, upon the attainment of abnormal current conditions the thermal strip is deflected outward so as to disengage the actuator and permit the contact member to move to its open-circuit position under the action of the springs 19^b, 19^b.

In addition to the main contacts 13^b and 16^b I have shown auxiliary carbon contacts. Associated with each of the main stationary contacts 13^b is an auxiliary carbon contact 35^b shown in detail in Fig. 6. The contact 35^b is held in place by a resilient strip 34^b which extends along the outer surface of the corresponding contact strip 13' and is held by the corresponding nut 4^b. Adjacent each of the main movable contacts 16^b is a carbon contact 37^b shown in detail in Fig. 7, this being held in place by means of the corresponding screw 18^b. The construction is such that when the contact member is moved from its closed-circuit position to its open-circuit position the two carbon contacts engage each other as the main contacts disengage each other and the carbon contacts remain in engagement for an instant so that any arcing that may occur takes place between the carbon contacts rather than between the main contacts.

Carried by the side plates 1^b, 1^b are two transverse pins 76, 76 held in place by means of nuts 77, 77. These transverse pins serve to assist in the proper spacing of the side plates, and the lower pin 76 serves as a means for holding the lower ends of the springs 19^b, 19^b. The pins 76, 76 also serve as means for guiding a vertically movable slide 78. This slide has a vertical slot through which the said pins 76, 76 extend, and as a matter of convenience the slide preferably comprises two parts 79 and 80. The front part 79 may be of insulating material. The said slide 78

carries an operating member or handle 31^b, the handle being provided with a rearward extending screw 81 which extends through a hole in the front member 79 and which is 5 threaded into the central portion of the rear member 80. Thus the handle serves to hold the two portions of the slide in engagement with each other. The weight of the slide and of the handle is such that the said parts tend 10 to move to their lower positions as shown in Fig. 9, and if necessary a spring (not shown) may be added to augment this tendency to move downward. The actuator 20^b has an arm 28^b and a link 24^b is interposed between 15 the arm 28^b and the said slide 78, the pivotal connections for the link 24^b being indicated at 27^b and 29^b respectively.

When all of the parts are in their circuit-closing positions as shown in Fig. 2 the pressure or stress applied by the springs 19^b, 19^b is transmitted through the thermal strip 21^b to the actuator 20^b and is thereby transmitted to the link 24^b which presses directly 20 forward substantially perpendicularly to the direction of movement of the slide 78. The parts may be arranged with the pivotal axis at 29^b at the same level with or above the axis 27^b as may be found necessary. The 25 result of the construction is that so long as pressure is applied to the actuator by means of the bi-metallic strip the link 24^b serves to hold the slide 78 and the handle 31^b in their upper positions as shown in Fig. 2 thus overcoming the tendency of the said slide and handle to 30 move downward by gravity. Thus the slide 78 and the link 24^b act as a restraining means to normally prevent the movement of the handle and actuator to open-circuit positions.

The handle 31^b may be moved downward 35 or upward as desired and when so moved it serves to move the contact member and the movable contacts thereon for ordinary switching purposes. Fig. 2 shows the parts in closed-circuit positions and Fig. 9 shows 40 the handle moved downward and the contact member swung upward so as to break the circuit.

Upon the attainment of abnormal current conditions, as for instance the passage of excess current, the bi-metallic strip 21^b is automatically disengaged from the actuator 20^b thus rendering inoperative the mechanical connection between the actuator and the contact member. The contact member then automatically moves to its open-circuit position under the influence of the springs 19^b, 19^b. It will be understood that this automatic movement takes place independently of the actuator so that the holding of the handle and 55 the actuator in closed-circuit position as shown in Fig. 10 will not interfere with the automatic opening. If the handle is not held in the closed-circuit position the handle and the actuator will immediately move to their 60 lower open-circuit positions as soon as the

pressure on the actuator is released by reason of the disengagement of the thermal strip therefrom. Obviously the release of the pressure on the actuator 20^b releases the pressure on the link 24^b thus permitting the slide and handle to move downward by gravity. Thus as the contact member moves toward its open-circuit position, the handle and the actuator move substantially simultaneously toward their open-circuit positions. The contact member will reach its open-circuit position first but the actuator and handle follow closely thereafter, the mechanical connection between the actuator and the contact member being substantially immediately restored by reason of the re-engagement of the thermal strip 21^b with the actuator 20^b. When the circuit is broken as the result of an ordinary overload the thermal strip is deflected only far enough to effect release and it very quickly cools sufficiently to effect re-engagement; but when the circuit is broken as the result of a short circuit the heating of the strip may be such as to deflect it more than enough to effect release and in such a case an appreciable interval of time may elapse before the strip cools sufficiently to effect re-engagement.

As shown the circuit breaker is enclosed in a casing 59^b which is held in engagement with the base 5^b by means of screws 66^b, 66^b. The casing 59^b has an opening 67^b in the front thereof through which the handle 31^b projects, the said opening being long enough to permit the vertical movement of the handle. It will be understood that the front member 79 of the slide prevents access through the said opening 67^b to the interior of the casing.

What I claim is:

1. In an automatic circuit breaker, the combination of a stationary support, an actuator pivotally mounted on the support, a contact member also pivotally mounted on the support and biased for movement independently of the actuator to its open circuit position, electro-responsively controlled means serving to effect operative mechanical connection between the actuator and the contact member and acting to release said mechanical connection under abnormal current conditions to permit the contact member to automatically move independently of the actuator to its said open circuit position, a manually operable slide carried by the stationary support and guided for rectilinear movement, and means connecting the slide with the actuator whereby movement of the slide to an off position normally effects corresponding pivotal movement of the actuator and the contact member to corresponding on and off positions for ordinary switching purposes.
2. A circuit breaker as set forth in claim 1 wherein the means connecting the slide with the actuator is a link pivotally connected with

the said slide and the said actuator respectively.

3. In an automatic circuit breaker, the combination of a main body comprising two spaced substantially parallel side plates, an actuator pivotally mounted between the plates for movement about a transverse axis, a contact member movably mounted between the plates and biased for movement independently of the actuator to its open-circuit position, an electro-responsively controlled mechanical connection between the actuator and the contact member which connection is normally operative and is automatically rendered inoperative upon the passage of excess current to permit the contact member to automatically move independently of the actuator to its open-circuit position, a manually operable slide carried by the plates and guided for rectilinear movement in a direction parallel therewith, and a means connecting the slide with the actuator and enabling the slide to move both the actuator and the contact member for ordinary switching purposes.

4. A circuit breaker as set forth in claim 3 wherein the means connecting the slide with the actuator is a link pivotally connected therewith for relative movement about axes parallel with the pivotal axis of the actuator.

5. A circuit breaker as set forth in claim 3 wherein the slide extends transversely between the side plates near the front thereof and is guided at its edges by the said plates.

6. A circuit breaker as set forth in claim 3 wherein there are transverse pins between the side plates and wherein the slide has a slot through which the pins extend, the length of the slot permitting the required rectilinear movement of the slide and the pins serving as guides for such movement.

7. In an automatic circuit breaker, the combination of a main body comprising two spaced substantially parallel side plates, an actuator pivotally mounted between the plates for movement about a transverse axis, a contact member movably mounted between the plates and biased for movement independently of the actuator to its open-circuit position, an electro-responsively controlled mechanical connection between the actuator and the contact member which connection is normally operative and is automatically rendered inoperative upon the passage of excess current to permit the contact member to automatically move independently of the actuator to its open-circuit position, two transverse pins extending between the side plates near the front thereof, a two-part slide having one part behind the pins and the other part in front thereof so that the pins serve to guide the slide for rectilinear movement, a handle connected with the slide, and a means connecting the slide with the actuator and enabling the slide to move both the actuator and the

contact member for ordinary switching purposes.

8. A circuit breaker as set forth in claim 7 wherein the handle is located at the front of the slide and serves to prevent separation of the two parts thereof.

9. An automatic circuit breaker comprising in combination, a movable contact member biased toward its open-circuit position, a manually operable pivotally mounted actuator biased toward its open-circuit position and normally mechanically connected with the contact member so as to be capable of operating it, rectilinearly movable slide relatively movably connected with the actuator to operate it and the contact member for ordinary switching purposes, a restraining means adapted to prevent automatic movement of the actuator and slide from their closed-circuit positions to their open-circuit positions, the said restraining means being rendered effective by the relative movement between the slide and actuator as the former moves the latter to its closed-circuit position, and an electro-responsive means serving upon the passage of excess current to release the contact member from the actuator so as to permit it to automatically move independently of the actuator to open-circuit position and also serving to render the restraining means ineffective so as to permit the slide and actuator to automatically move to open-circuit positions substantially simultaneously with the movement of the contact member to open-circuit position.

10. An automatic circuit breaker comprising in combination, a movable contact member biased toward its open-circuit position, a pivotally movable actuator, an electro-responsively controlled mechanical connection between the actuator and the contact member which connection is normally operative and is automatically rendered inoperative upon the passage of excess current to permit the contact member to automatically move independently of the actuator to its open-circuit position, a rectilinearly movable slide biased toward its open-circuit position, and means associated with the slide and the actuator and normally enabling the slide to operate both the actuator and the contact member for ordinary switching purposes, the last said means serving when the slide and actuator are in closed-circuit positions to prevent automatic movement thereof to open-circuit positions so long as the actuator is biased to open-circuit position by reason of the mechanical connection between it and the contact member and the said means upon the inoperativeness of the said mechanical connection releasing the slide and actuator to permit automatic movement thereof to open-circuit positions substantially simultaneously with the movement of the contact member to open-circuit position.

11. A circuit breaker as set forth in claim 10 wherein the contact member and actuator are pivoted for movement about a common axis and are maintained in fixed relationship 5 to each other during normal switching movements.
12. An automatic circuit breaker comprising in combination, a movable contact member biased toward its open-circuit position, a 10 pivotally movable actuator, an electro-responsively controlled mechanical connection between the actuator and the contact member which connection is normally operative and is automatically rendered inoperative upon 15 the passage of excess current to permit the contact member to automatically move independently of the actuator to its open-circuit position, a slide movable in a direction perpendicular to the pivotal axis of the actuator 20 and biased toward its open-circuit position, and a link pivoted at its ends to the slide and the actuator respectively and normally enabling the slide to operate both the actuator and the contact member for ordinary switching 25 purposes, the said link being substantially perpendicular to the direction of movement of the slide when the slide and actuator are in closed-circuit positions thereby preventing automatic movement thereof to open-circuit 30 positions so long as the actuator is biased to open-circuit position by reason of the mechanical connection between it and the contact member and the said link upon the inoperativeness of the said mechanical connection 35 releasing the slide and actuator to permit automatic movement thereof to open-circuit positions substantially simultaneously with the movement of the contact member to open-circuit position.
- 40 13. An automatic circuit breaker comprising in combination, a rectilinearly movable operating member, a pivotally movable actuator, a pivotally movable contact member biased independently of the actuator toward 45 its open-circuit position and releasably connectible with the actuator so as to be normally controlled thereby for movement to its closed-circuit or its open-circuit position, an electro-responsive means bodily movable as 50 an entirety when the actuator and contact member are moved, the said electro-responsive means serving upon the attainment of abnormal current conditions to cause the release of the contact member from the actuator 55 for independent automatic circuit-opening movement, and a means enabling the rectilinearly movable operating member to effect the movement of the pivotally movable actuator and also normally serving to prevent 60 automatic movement of the operating member and actuator from their closed-circuit position, the said means being rendered effective to prevent such automatic movement as 65 the result of stress transmitted from the contact member to the actuator through the said
- mechanical connection and becoming ineffective for such purpose upon the diminution or absence of the aforesaid transmitted stress.
14. An automatic circuit breaker as set forth in claim 13, wherein the means enabling 70 the operating member to effect the movement of the actuator is a pivoted link and wherein the electro-responsive means is an electro-thermal strip serving in and of itself as the mechanical connection between the actuator 75 and the contact member and adapted to become inoperative as such connection upon the passage of excess current.
15. In an automatic circuit breaker, the combination of a main body comprising two 80 spaced substantially parallel side plates, two conducting cross members connecting the plates adjacent opposite ends thereof, a manually operable actuator pivotally mounted between the plates for movement about a 85 transverse axis, a contact member pivotally mounted between the plates for movement about the same transverse axis independently of the actuator, the said contact member being biased toward its open-circuit position, two 90 movable contacts electrically connected with each other and carried by the contact member at opposite sides thereof, electro-responsively controlled means including a mechanical connection between the actuator and the contact 95 member which connection is normally operative and is automatically releasable upon the passage of excess current to permit the contact member to automatically move independently of the actuator to its open-circuit 100 position, two similar stationary contacts carried respectively by the side plates in position to be respectively engaged and disengaged by the movable contacts on the contact member and each comprising a resilient strip 105 connected with the corresponding side plate adjacent one of the cross members, the two strips both extending in the same direction longitudinally of the side plates, means electrically connecting one strip directly with the immediately adjacent cross member, and a conductor extending longitudinally of the corresponding side plate for electrically connecting the other strip with the cross member 110 at the opposite end.
16. A circuit breaker as set forth in claim 15 wherein at least one of the cross members is threaded at its ends and is provided with nuts connecting it with the side plates, and wherein the two contact strips are respectively held in place by the two nuts on the said cross member, one strip being electrically connected with the cross member and the other being insulated therefrom.
- In testimony whereof I have hereunto set 125 my hand this 11th day of January, 1929.
- JOSEPH SACHS.
